UNITED STATES PATENT OFFICE.

ANDREW BOHNAK, OF McCLELLANDTOWN, PENNSYLVANIA.

RIFLE-FEEDING ATTACHMENT.

Application filed February 18, 1922. Serial No. 537,553.

To all whom it may concern:

Be it known that I, ANDREW BOHNAK, citizen of Poland, residing at McClellandtown, in the county of Fayette and State of Pennsylvania, have invented certain new and useful Improvements in Rifle-Feeding Attachments, of which the following is a specification.

This invention relates generally to rifles, having more particular reference to a magazine attachment arranged to permit of the firing of a large number of shots without recharging.

The invention has for a general object to provide a magazine attachment which will contain a much larger number of cartridges than magazines now in use in connection with rifles.

For further comprehension of the invention, and of the objects and advantages thereof, reference will be had to the following description and accompanying drawings, and to the appended claims in which the various novel features of the invention are more particularly set forth.

Fig. 1 of the drawings is a partial side view of a rifle having my improved magazine attachment applied thereto.

Fig. 2 is a transverse vertical section on the line 2—2 of Fig. 1.

Fig. 3 is a transverse section on the line 3—3 of Fig. 1.

Referring now to the drawings 10 indicates the barrel of the rifle, and 11 the stock. In the rear of the barrel 10 are two transverse openings 12 and 13 respectively, for reception of the cartridge and discharge of the shell. The rifle is provided with a breech bolt 14 of suitable construction which moves the cartridges forward into the breech and extracts the shells.

My improved magazine attachment comprises a box 20 or magazine proper, which may be placed on any suitable support and which is provided with the vertically spaced inclined partitions or shelves 21 upon which the cartridges are placed as indicated in Fig. 2. The box 20 is closed on one side by a hinged door 23 provided with a snap fastener 24.

Extending upwardly across that end of the box 20 toward which the partitions 21 incline downwardly is one reach of an endless carrier belt 25 which in effect, forms the end of the box, the upwardly moving reach of the belt being spaced apart from

the ends of the partitions 21 a distance slightly greater than the diameter of the cartridges. Fixed to this belt are fingers 26 arranged in corresponding rows along opposite sides of the belt and spaced from one another longitudinally of the latter a distance equal to the spacing of the partitions 21. These fingers are curved concavely on their forward sides as shown so as to properly hold the cartridges, the latter being indicated at 28 in Fig. 2.

The carrier belt 25 is looped at lower and upper ends respectively around rollers 30 and 31 journaled in chute-like member comprising the side boards 32 and connecting board 33. The belt 25 is advanced by rotation of the upper roller 31 and to ensure of proper engagement the roller 30 is provided with teeth 35 engaging in holes 36 in the belt. As each cartridge is carried over the top of the roller 31 it falls by gravity on a series of inclined fingers 37 projecting from the barrel and rolls into a chamber 39 in front of the bolt 14 and alining with the bore of the barrel. It will be understood that the fingers 26 and 37 are staggered with respect to each other. The carrier supporting member 32, 33 may be secured to the side of the stock 11 by means of screws 42, passing through ears 43 formed on the upper ends of the sideboards 32, and screwed into the stock permitting of its ready removal when desired.

The carrier belt 25 is intermittently advanced by means of a sleeve 45 reciprocable on a double screw 46 extending along and journaled under the stock, the sleeve having a rib 47 on one side engaging in a longitudinal slot 48 in the under face of the stock 95 to hold it against rotation. Fixed to one end of the screw 46 is a gear pinion 50 meshing with a larger gear 51 journaled in one of the side boards 32, this gear 51 in turn meshing with a gear 52 fixed co-axially to 100 roller 31.

To cause reciprocation of sleeve to rotate screw 46 the former has pivoted therein between its ends as at 53 an elongated stud 54 which engages in the threads of the screw. 105 As shown in Fig. 1 of the drawings the two threads of the screw unite at their ends in straight grooves 55 and it will be noted that these straight grooves are circumferentially offset with respect to the apices 56 of the two threads so that when the stud travels through one thread until it engages in the

straight portion 55 its opposite movement will cause it to engage in the other thread so that the screw is always rotated in the one direction.

5 In the operation of the rifle the cartridges are delivered successively to the barrel by reciprocating the sleeve 45, the extraction being done in the usual manner by the bolt 14. To prevent any chance of the cartridges 10 being thrown by centrifugal force off the upper roller 31 I provide a curved hood 60 which partially surrounds the latter.

While I have shown and described a preferred embodiment of my invention it is to 15 be understood that wide changes and variations might be made in the construction without departing from the spirit and scope of the invention.

Having thus described my invention what 20 I claim as new and desire to protect by Letters Patent of the United States is as follows:

1. In combination with a rifle, a magazine box, an endless carrier belt leading from 25 said box to the rifle and provided with cartridge holding fingers, a screw swiveled in the rifle and adapted by rotation to advance said carrier belt, and a sleeve reciprocable on said screw and adapted by reciprocation

to rotate the latter, said screw being formed 30 with right and left threads meeting at their ends, and a pivoted stud carried by said sleeve and adapted to engage the respective threads as the sleeve is moved in opposite direction.

35

2. In combination with a rifle, a magazine attachment comprising a box having a number of vertically spaced partitions inclining downward toward one end of the box, a chute-like frame element connected 40 at its lower end to said box and at its upper end to the side of the rifle, a pair of rollers journaled in opposite ends of said frame element the rifle having a receiving opening 45 for cartridges formed in the side thereof adjacent the upper one of said rollers, a series of fingers projecting outwardly from the lower side of said opening toward the said upper roller, an endless carrier belt looped over said rollers and provided with 50 carrier fingers for cartridges and a screw swiveled on the rifle, gear connections between said screw and one of said rollers, a sleeve adapted to reciprocate on said screw to rotate the same.

55

In testimony whereof I have affixed my signature.

ANDREW BOHNAK.
